J. H. GRAPEVINE.

TROLLEY STOP.

APPLICATION FILED MAY 31, 1916.

1,254,683.

Patented Jan. 29, 1918.

Inventor,
James Hudson Grapevine
J. H. Grapevine
Atty.

UNITED STATES PATENT OFFICE.

JAMES HUDSON GRAPEVINE, OF PEORIA, ILLINOIS.

TROLLEY-STOP.

1,254,683.

Specification of Letters Patent. Patented Jan. 29, 1918.

Application filed May 31, 1916. Serial No. 103,877.

To all whom it may concern:

Be it known that I, JAMES HUDSON GRAPEVINE, a citizen of the United States, residing at Peoria, in the county of Peoria and State of Illinois, have invented certain new and useful Improvements in Trolley-Stops, of which the following is a full, clear, and exact description, reference being had to the accompanying drawing, forming part of this specification.

My invention relates to means for preventing overhead carrying trolleys from running out of or off of the ends of their tracks.

The object of my invention is to provide means, which will be automatic in their action, capable of being operated to permit the removal of the trolley for oiling or repairs, and which after having been so operated will, when released, be restored by gravity to operative position.

Other objects of my invention will appear and be described as the specification proceeds.

The novelty of my invention will be hereinafter more fully set forth and specifically pointed out in the claims.

In the accompanying drawing:

Figure 1 is a side elevation, partially broken away, of an end of a trolley track, its supporting timber, and showing one form of the embodiment of my invention as applied adjacent to the end of the track.

Fig. 2 is an end view of Fig. 1 looking toward the left.

Fig. 3 is a perspective view of the stop.

Fig. 4 is an end view of a modified form of stop supporting bracket.

The same numerals of reference are used to indicate identical parts in all the figures.

For purposes of illustration I have shown a swinging stop 1 consisting of the side walls 2, front wall 3, lower flange 4, cross bar 5, and counterbalance weights 6.

The side walls 2 are perforated as at 7 to receive the bolt 8 which passes through said perforations and through a supporting bracket 9, which latter is provided with lateral extensions 10 by means of which, and the bolts 11, the supporting bracket is secured to the under side of the timber 12.

The track 13, carrying the trolley 14, which latter is provided with the depending hook 15, is supported by means of bolts 16 passing through the timber 12 after the usual or any suitable manner.

It is to be understood that the timber 12 is suitably secured either against the ceiling or to the under side of the roof trusses of the building in which the mechanism is mounted though the support for the timber 12, not forming any part of or affecting my present invention, is not shown.

To adapt my device for use in connection with trolleys which are wider than the one shown, the supporting bracket 9 may be provided with depending ears 17 as shown in Fig. 4, instead of a single wide depending lug or eye as shown in Fig. 2, and the end wall 3, bottom flange 4, and cross bar 5 of the stop 1 may be lengthened by an amount 70 corresponding to the increase in width of the supporting bracket.

In its normal or operative position, shown in full lines in Fig. 1, the end wall 3 of the stop 1 lies adjacent to and across the end 75 of the track 13 to effectually prevent the trolley 14 from running out of the end of the track and falling to the floor, thereby dropping the load which may be supported by the trolley. When it is desired to remove 80 the trolley from its track for purposes of oiling or repairs, or when it is desired to place other trolleys in service the operator uses the bottom flange 4 of the stop 1 as a finger hold to partially rotate the stop on 85 the bolt 8 to the position shown by the dotted lines in Fig. 1, thereby bringing the end wall 3 downwardly away from its position at the end of the track and permitting the removal of the trolley from its track or the 90 introduction of other trolleys thereto, whereupon the operator releases his hold upon the stop and the stop immediately returns to the position shown in full lines in Fig. 1.

To prevent the stop 1 from being turned 95 to a point from which it would not return by gravity, the cross bar 5 is provided and so shaped and located that it forms a limit for the movement of the stop by coming in contact, when the stop is operated, with the head of one of the bolts 11, or the cross bar 5, may be located in such a position that it will come against some other stationary part to act as a movement limit.

While I have shown the stop as applied 105 to a trolley having a track in the form of a channel it is evident that by modifying the method of mounting, the stop may be applied to other forms of trolleys with equally good results.

Having thus fully described my invention, I claim:

1. A stop for trolleys comprising a pivotal mounting for the stop, said mounting being beyond the end of a trolley track, a stop structure mounted thereon and normally occupying a position slightly beyond the end of a trolley track in such manner that the trolley will be prevented from accidentally running over the end of its track, and means for operating said stop structure to permit the removal or introduction of trolleys from or to the track.
2. A trolley stop comprising a member located beyond the end of a trolley track and separate therefrom and affording a pivotal mounting for a stop, a gravity retained stop mounted on said member, and means for operating said stop.
3. A trolley stop comprising a member located beyond the end of a trolley track and separate therefrom and affording a pivotal mounting for a stop, a gravity maintained stop mounted on said member, means for

operating said stop, and a movement limit 25 carried thereby in such manner that when said stop is operated to a point at which the movement limit becomes effective the stop will return to operating position by gravity.

4. A trolley stop comprising a counter-weighted stop structure mounted beyond the end of a trolley track, an end wall thereon adapted to be maintained in operative position adjacent the end of the track by a counterweight, a finger-hold for operating the 30 stop, and means for supporting the stop structure adjacent the end of a trolley track.

5. A trolley track comprising a pair of apertured side walls, an end wall normally lying adjacent a trolley track, a bottom 40 flange affording a finger-hold for operating the stop, a cross bar forming a movement limit, counterweights for normally retaining said end walls in operative position, a supporting bolt or pin passing through the 45 perforation in said side walls, and a supporting bracket for said bolt or pin.

JAMES HUDSON GRAPEVINE.
